United States Patent

Des. 236,675
Patented Sept. 9, 1975

236,675

RECORD STAND

Arne P. Darnell, Urshult, Sweden, assignor to Perstorp AB, Perstorp, Sweden

Filed Nov. 19, 1973, Ser. No. 417,050

Claims priority, application Sweden June 7, 1973

Term of patent 14 years

Int. Cl. D6—04

U.S. Cl. D6—185

FIG. 1

FIG. 3

FIG. 1 is a perspective view taken from one side of a record stand, showing my design;

FIG. 2 is a perspective view taken from the side opposite that of FIG. 1; and

FIG. 3 is an elevation of the front open end of the record stand.

I claim:

The ornamental design for a record stand, as shown.
